(57) **CLAIM**

The ornamental design for a computer keyboard, as shown and described.

DESCRIPTION

FIG. 1 is a perspective view of a computer keyboard;
FIG. 2 is a rear perspective view of the computer keyboard of FIG. 1;
FIG. 3 is a top plan view of the computer keyboard of FIG. 1;
FIG. 4 is a bottom plan view of the computer keyboard of FIG. 1;
FIG. 5 is a right-side plan view of the computer keyboard of FIG. 1;
FIG. 6 is left-side plan view of the computer keyboard of FIG. 1;
FIG. 7 is a front plan view of the computer keyboard of FIG. 1; and,
FIG. 8 is a rear plan view of the computer keyboard of FIG. 1.
The broken lines in FIGS. 2-6 and 8 depict portions of the computer keyboard that form no part of the claimed design.

1 Claim, 8 Drawing Sheets
